UNITED STATES PATENT OFFICE.

JAMES C. BROWNFIELD, OF SEATTLE, WASHINGTON.

LOG RAFT AND TOWING BRIDLE THEREFOR.

Application filed August 11, 1924. Serial No. 731,390.

To all whom it may concern:

Be it known that I, JAMES C. BROWNFIELD, a citizen of the United States of America, and resident of the city of Seattle, 5 in the county of King and State of Washington, have invented certain new and useful Improvements in Log Rafts and Towing Bridles Therefor, of which the following is a specification.

10 My invention relates to rafts which are particularly intended for rafting logs over long distances and in water which is liable to be rough.

It is, therefore, an object of my invention 15 to provide a raft in which the individual logs comprising the same are securely held yet which is flexible to an extent that each may have movement independent of the other logs, and so arranged that if one or 20 more logs becomes detached from the raft it has no tendency to detach other logs therefrom.

A further object is the provision of such 25 a log raft in which all of the logs are floating and a towing bridle therefor by means of which all of the logs are attached more or less directly to a central line which is directly connected to the towing line, thus causing the strains in towing to extend along 30 lines which are nearly straight.

A further object is the provision of such 35 a raft which may be made up cheaply, in shallow water if necessary, and without the necessity for constructing cradles, wharfs or like structures, or the employment of derricks.

A further object is the provision of such a 40 raft and towing bridle which may be made in sections and which will tow the logs segregated in sections, as many sections as are desired, consistent with the strength of the towing members, being employed in the raft.

A further object is the provision of a towing 45 bridle for such rafts which renders the formation of the raft simple and convenient.

Other objects will be ascertained from a 50 study of the drawings attached hereto, which show a number of preferred forms of my invention, and of the specification and claims terminating the same.

55 My invention comprises those novel parts and combinations thereof which are shown in the accompanying drawings, described in the specification and particularly defined by the claims terminating the same.

In the accompanying drawings I have shown my invention in the forms which are now preferred by me.

The figures are plan views, of various 60 forms of the raft. Figure 1 being the form now most preferred by me, and Figures 2, 3 and 4 being modifications of the same general idea.

It is customary to prepare rafts of tree-length logs for long distance towing by binding them with ropes and chains into a more or less rigid cigar-shaped mass, some 65 of the logs being submerged and others lying upon and being buoyed by the submerged logs. Such rafts are of the general type shown in the patent to Davis, No. 1,142,239. They have proven fairly satisfactory, but occasionally, in rough weather, 70 will be broken up, and once such a raft starts to break the loss of the entire raft is probable. The safety, therefore, of the entire 75 raft is more or less dependent upon each cable or chain which enters into the construction of the raft, and if a single cable 80 or chain breaks the raft is liable to destruction. This necessitates the use of heavy cables and chains and makes the raft expensive. Further, such rafts require special 85 derricks and deep water in which to build them. There are numerous good harbors 90 along the Pacific Coast which are too shallow to permit the formation of any rafts except of floating logs. Rafts deeper than a single log, when under way draw considerable water and are difficult to tow.

It has also been proposed to form rafts 95 of floating logs, but so far as is known to me such rafts, while capable of being constructed in shallow water, are open to the objection that their safety is chiefly dependent upon a few of the many logs embodied in the raft, and if the key logs are lost the entire raft will go to pieces. Such rafts, to 100 avoid the obvious danger of loss, must be strongly bound together and their cost is thus increased.

According to my invention I propose to 105 form a raft having the advantage of the floating rafts, that is to say, one which may be made up in shallow water and in sections if necessary, the sections to be connected after their formation, and one in which the cables or chains may be comparatively 110 light and inexpensive, and in which the loss of one or more logs will not affect the remainder nor render the remainder more

liable to break away. Such a raft as I propose will also include the advantages of flexibility and consequent ease of handling and convenience in manufacture and assembly.

The raft proper is made up of a series of logs each floating upon the surface. Preferably such logs are arranged in sections, the logs 1 of each section extending parallel and longitudinally of the raft so that the rear ends of the logs in a forward section will lie adjacent the forward ends of the logs in a rear section. To secure together the logs in a given section I employ members 2 such as cables, which I may term side lines, and which are connected to the forward ends of the logs 1 of each section. This may be done by boring all of the forward ends of the logs, as indicated at 3, and passing the side lines 2 through these bores, securing a knob or like member 4 upon the outer end of the side line to keep it from pulling through the bores 3 in the various logs. For each section in the preferred form two such side lines are employed, these extending at either side of a master line 5 which extends from end to end of the raft and centrally thereof.

Preferably this master line is made up of a plurality of sections, each section having at its forward end a clevis 6 or like detachable securing means by which it may be connected to the rear end of the next section of the master line ahead of it, and having connected to its rear end the two side lines 2. These side lines may be permanently or detachably secured to the end of their corresponding master line section, and it is to a large extent immaterial whether this connection is to the forward end or to the rear end of the master line section.

The master line itself may be either a cable, chain, or like flexible member, or may be composed, as in Figure 3, of a series of logs 5', flexibly connected, as by the cables 7. In the form shown in Figure 4 the master line sections are again divided, each section 5" having a single side line 2 secured thereto, the side lines extending in opposite directions for alternate master line sections. It is preferable that the side lines be cables or like flexible members so that when a strain is placed upon the master line the side lines will tend to drag and align themselves with the master line, thus to place the towing strain as nearly as possible in a straight line from the tow line to the outermost of the logs 1. This will serve to press the logs 1 inward toward the master line, or at least their forward ends, but will leave their rear ends free to separate somewhat with the action of the waves, 60 They will each be quite free to take their own course, thus rendering the raft flexible,

able to pass through narrow spaces and able to absorb stresses which would seriously shake and damage a rigid raft.

Owing to the manner in which the logs are secured to the side lines, and the side line in turn are secured directly to the master line, no one log is dependent on any other log for its connection to the tow line. If any given log, either the outermost log in a section or an inner log, be torn from its connection to the side line 2, through tearing out the material between the holes 3 and the forward ends of the logs this will not tend to release or disengage any other log from the side line, but will merely make a gap which will be filled up by the tendency toward outward movement of the logs in each section, in towing. Thus if in heavy weather one or more logs is lost from a section, it will ordinarily have no effect upon the remainder of the raft. By forming the raft in sections it is made easy to assemble and the sections may be towed to an assembling point and there assembled into the entire raft. The side lines need not be extremely heavy, as they serve only to tow a relatively small number of floating logs and the strain upon them is nearly in a straight line direction. The master lines of course must be strong enough to carry the load of the raft behind them, but inasmuch as all the pull is in a straight line and is equalized by the spacing of the logs at opposite sides of the master line, this master line need not be as heavy as is ordinarily required for towing flexible rafts.

It may occasionally be found desirable to restrain somewhat the tendency of the rear ends of the logs of a section from floating outward from the section. To this end I have shown in Figure 2 a line 8 which is passed over the rear end of the logs of a section and which may be secured to the outer logs and to various intermediate logs, as is indicated at 9. In this manner the logs may be kept from spreading too greatly, although the raft still retains its flexible characteristics. It may also be desirable to employ more than one master line, but this I consider mere duplication. Also, if the master line requires strengthening, additional lines may be used to strengthen it, this being a matter of proper engineering.

What I claim as my invention is:

1. A raft comprising a single longitudinally extending back bone, members secured thereto at intervals and extending laterally therefrom at each side to leave their outer ends free, said members being flexibly connected to the backbone, and a plurality of sections of logs extending parallel to the backbone, the forward ends of each individual log in each section being secured to said laterally-extending members.

2. In a log raft, a plurality of logs ar-

- ranged in successive sections, the logs in each section being parallel and extending longitudinally, and the successive sections extending longitudinally of the raft, means 5 flexibly connecting the forward ends of each individual log in each section, and a single tension member extending longitudinally centrally of the raft, said connecting means being secured at its inner end to the said 10 tension member and its outer end being unrestrained.
3. A raft comprising a plurality of logs disposed in sections, the logs in each section being parallel and extending longitudinally, and the several sections being disposed longitudinally of the raft, a single master line extending from end to end of the raft, and side lines corresponding to each section secured thereto at intervals and 15 extending laterally therefrom at each side, each of said side lines being secured to the forward end of each individual log in the corresponding section, the rear ends of the logs being unconnected to said master line.
- 20 4. In a log raft, a plurality of logs arranged in sections, the logs in each section being parallel, and the sections being disposed with the forward ends of the logs of a rear section adjacent the rear ends of the 25 logs of a forward section, the forward ends of all of said logs being bored, a centrally positioned master line extending from end to end of the raft, and a side line passed through the bores of the logs in each section
- at either side of said master line, the inner 35 ends of the side lines being secured to the master line.
5. In a log raft, a plurality of logs arranged in sections, the logs in each section being parallel and extending longitudinally, 40 a master line section extending forwardly from each section of the raft, means for securing the several sections of the master line together to form a line extending from end to end of the raft and centrally thereof, and 45 side lines secured to the rear ends of each section of the master line and extending laterally at each side thereof, said side lines being secured to the forward ends of the logs in the corresponding section of the raft. 50
6. A towing bridle for log rafts comprising a master line and a plurality of side lines connected thereto at log length intervals by one end only, and extending laterally therefrom, and of a length corresponding 55 to the combined widths of a plurality of logs.
7. A towing bridle for log rafts comprising a master line formed in sections of log length connected end to end, and a pair of 60 side lines secured by one end only to an end of each section of the master line and extending at opposite sides thereof to a distance corresponding to the combined widths of a plurality of logs. 65

Signed at Seattle, King County, Washington, this 1st day of August, 1924.

JAMES C. BROWNFIELD.
